UNITED STATES PATENT OFFICE.

EARL S. GRAHAM AND EARL S. GRAHAM, JR., OF DALLAS, TEXAS.

REFRIGERATING CONTAINER.

Application filed April 29, 1927. Serial No. 187,634.

This invention relates to new and useful improvements in refrigerating containers.

The object of the invention is to provide a container, tank, body or receptacle, wherein 5 amplified cooling surfaces are provided between the refrigerant compartment and the storage compartment, thus making for a prolonged refrigerating period with a given quantity of refrigerant.

10 A further object of the invention is to confine the heat exchange to a restricted space completely surrounding the storage compartment.

Another object of the invention is to 15 equip the wall separating the refrigerant compartment from the storage compartment with a plurality of longitudinal fins constructed of a comparatively thin metal suitable for the purpose, whereby a maximum 20 heat exchange is effected and a constant low temperature, approximating the freezing point of water, is maintained in the storage compartment.

A still further object of the invention is to 25 provide longitudinal fins which extend transversely substantially from the storage compartment to the refrigerant compartment for the purpose of conducting heat and cold direct from one compartment to the other, 30 but over greatly amplified surfaces, whereby an effective exchange is carried out and a greater prolonged refrigerating period is maintained in the storage compartment than is had with the usual container.

35 A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a horizontal cross-sectional view taken on the line 1—1 of Fig. 2 and showing 45 a container constructed in accordance with the invention and in position in a cabinet,

Fig. 2 is a transverse vertical sectional view taken on the line 2—2 of Fig. 1, and

50 Figs. 3, 4 and 5 are plan views of respective modified forms in which the invention may be carried out.

In the drawings the numeral 10 designates 55 a tank which may be of any suitable shape and which we have shown in Figs. 1 and 2 as rectangular in plan. The tank is preferably formed of galvanized sheet metal, but

may be made of any material suitable for the purpose.

In Figs. 1 and 2 the tank is shown mounted in a cabinet 11 and surrounded by 60 suitable heat insulating material 12. The cabinet has a top 13 provided with a closure ring 14 and a lid 15. It is to be understood that the tank may be mounted and used wherever found practical and the showing 65 of the cabinet is merely for the purpose of illustrating a practical use for the container.

Within the tank are formed a storage compartment A and a refrigerant compartment B. These compartments are defined and 70 separated by a continuous heat exchange wall C. This wall preferably extends from the bottom of the tank to the top portion thereof. The wall may be given various shapes in plan and its particular construction 75 may vary in accordance with the form in which it is employed.

In Figs. 1 and 2 we have shown the wall C as circular and formed of comparatively thin sheet metal bent upon itself at short 80 intervals to form inwardly directed radial fins 16 connected by short webs 17 constituting the outer surface of the wall. The fins and the webs extend vertically and the inner vertical ends of the fins are closed, 85 while their outer vertical ends, between the webs, are open. Very satisfactory results have been obtained by the use of sheet copper in forming the wall C. The wall is, of course, made continuous circumferentially, 90 the edges of the sheets being suitably welded, soldered, or otherwise secured together.

Brine or any other suitable refrigerant is placed in the compartment B of the tank 10 and, of course, a fluid-tight joint is made at 95 the bottom of the wall C so that this fluid cannot flow into the compartment A. In Fig. 2 a cap ring 18 is fastened on the upper end of the wall C so as to prevent anything from falling down into the spaces between 100 the fins and also to protect the upper edges from injury. Suitable braces 19 extend from the webs 17 to the side walls of the tank 10 for holding the wall C in place.

The liquid refrigerant contained in the 105 compartment B will flow into the fins 16 and will also contact with the webs 17. Each fin comprising two walls, each substantially equal in width to the webs 17, it is obvious that approximately twice as much 110 surface is exposed to the refrigerant by the fins as is exposed by the webs. It is also

pointed out that three times as much surface is exposed to the refrigerant as would be had where a smooth continuous circular wall was used.

Substantially the same surface area of the wall C is exposed in the compartment A as is exposed in the compartment B and, therefore, the heat generated by the commodity contained in the compartment A is effectively dissipated or radiated by the fins and webs. By the use of thin metal, the fins and webs are chilled by the refrigerant so that the heat radiation in the compartment A is so effectively absorbed as to reduce the temperature in said compartment A to approximately that of the compartment B. It is obvious that the amplified surface area provided by the fins 16 and the webs 17 will be so extensive as to hold down the generation of heat and thereby prolong the period of refrigeration. A metal can or any other commodity may be placed in the compartment A and ice-cream, or any other product, may be maintained at a proper temperature for a greatly increased period of time than is possible with the ordinary containers.

In Fig. 3 is shown a form of container in which the same tank 10 is employed, but the wall C is composed of a continuous outer cylinder 20 to the inner surface of which a plurality of inwardly directed vertical fins 21 are secured. These fins are preferably L-shaped in plan so that they may be more readily fastened to the cylinder, but this is not essential. These inwardly directed fins are spaced in comparatively close order and with the cylinder will function the same as the fins 16 and webs 17. As a further illustration of the many forms in which the invention may be carried out, fins 22 are shown in Fig. 4 as applied to the outer side of a rectangular box 20' instead of the inner side, in which case the compartments will be reversed.

In Fig. 5 a rectangular tank 10' is shown and the compartment B is separated from

the compartment A by a rectangular wall C. This wall comprises vertical outer plates 23 having vertical L-shaped fins 24 secured to its inner surface, said fins being similar to the fins 21 and 22 and spaced accordingly. The plates 23 are held by braces 25 connected with the tank 10'. By making the wall C rectangular, the storage compartment A is enlarged and the refrigerating surface is increased.

It is important that the fins be spaced close enough to give sufficient amplification of the refrigerating surface as to secure the desired prolongation of the refrigerating period. The fact that the refrigerating liquid comes in direct contact with the elements of the wall C is, of course, responsible for the success of the container.

Various changes in the size and shape of the different parts, as well as modifications and alterations, may be made within the scope of the appended claims.

What we claim, is:

1. In a refrigerating container, a tank, and a vertical storage container spaced from the walls of the tank and open at its opposite ends with its lower end secured to the bottom of the tank, the wall of said container being formed with a continuous series of radially directed fins and presenting a substantially plane surface at the space next the tank.

2. In a refrigerating container, a tank, a storage container spaced from the wall of the tank and having its wall formed from a continuous sheet bent upon itself to produce a series of inwardly directed fins having separated walls disposed solely within the container and a substantially plane outer surface, an annular cover seated upon the upper end of said sheet to enclose said fins, and braces extending from the container to the tank.

In testimony whereof we affix our signatures.

EARL S. GRAHAM.
